UNITED STATES PATENT OFFICE.

ALFRED B. WALES, OF WHITMAN, MASSACHUSETTS, ASSIGNOR TO LORENZ MUTHER,
OF NEWTON, MASSACHUSETTS.

WEB FEEDING AND CUTTING APPARATUS.

1,398,581.

Specification of Letters Patent. Patented Nov. 29, 1921.

Substitute for application Serial No. 165,119, filed April 28, 1917. This application filed April 28, 1920.
Serial No. 377,416.

To all whom it may concern:

Be it known that I, ALFRED B. WALES, a citizen of the United States, residing at Whitman, in the county of Plymouth and 55 State of Massachusetts, have invented a new and useful Improvement in Web Feeding and Cutting Apparatus, of which the following is a specification, reference being had therein to the accompanying drawings.

10 This invention relates to a web-feeding and cutting apparatus and with regard to certain more specific features thereof to devices for cutting a continuous web into a plurality of predetermined or variable short 60 lengths.

15 It is one of the objects of the present invention to provide a device of the character mentioned which shall be simple in construction, durable and inexpensive to manufacture.

20 Another object resides in the provision of a rapidly operative and reliably efficient feeding and gripping means whereby a tape or web may be presented to a cutter.

25 Other objects will be in part obvious and in part pointed out hereinafter.

30 The invention accordingly consists in various features of construction, combination of elements and arrangements of parts 75 which will be exemplified by the construction hereinafter set forth and the scope of the application of which will be indicated by the following claims.

35 In the accompanying drawing, wherein is shown one of various possible embodiments of the invention, Figure 1 is a top plan of a web-feeding and cutting machine embodying the invention; Fig. 2 is a view of the same in side elevation; Fig. 3 is a fragmentary view of the same in end elevation.

40 Referring now more particularly to the drawings wherein similar reference characters refer to similar parts throughout the several views, there is indicated at 1 a support or standard having a longitudinally extending web 2 and a transversely extending web or lug 3. A hub 4 is provided on the web 2 serving as the journal for a main driving shaft 5. This shaft carries a rotatable feed element 6 which in the present

embodiment is shown as comprising a pair of segmental feed rollers 7 and 8, the member 8 being fixed on the main driving shaft and the member 7 being adjusted and secured to the member 8 by means of the slot 55 and screw connection illustrated at 9 in Fig. 2. It will be noted that this construction will permit a co-extensive arrangement of the segmental feed rollers or, if it is desired to vary the length of the feeding 60 surface, that the members may be moved into different relative angular positions and secured therein. The longitudinal web 2 is provided on one side with a short laterally extending lug 10 in which there is fixed 65 a gripping member 11.

Secured to the inner side of the web 3 is a right angled spring strip 12 which serves as a yielding bed for the tape or web during its passage from the source of supply to the 70 cutting means which will be later described. This spring strip has another function in that it is adapted to coöperate with the rotatable feed element to press the tape or web against the knurled or roughened surface of 75 the feed roller. And the spring strip has still another function in that it coöperates with the fixed gripper member 11 at certain times to clamp the tape or web in position to be picked up by the feed rollers. 80 Suitable side registers 13 and 14 are provided and designed to prevent lateral displacement of the tape or web in the operation of the device.

The cutting mechanism comprises a fixed 85 shear member 15 secured to the web 3 of the support 1 and a movable shear element or knife 16 pivotally mounted as at 17 to co-operate with the fixed shear element 15. Spring means 18 are provided for normally 90 holding the shearing elements angularly spaced and a pin 19 is carried by the segmental feed roller 8, which is fixed to the main driving shaft. This pin in its path of travel with the feed roller mentioned, actuates a lever 20 pivotally mounted at 21, which lever bears upon the upper edge of the movable cutter 16 and is designed to move the latter to shear a length of web 95 which has been fed.

The operation of the device is as follows: The end of the web-roll or tape is led into the machine by springing apart the gripper members 11 and 12, the feed roll being rotated to the non-feed position. The forward end of the tape is placed directly in position to be engaged by the feed roller in its forward rotation. When this engagement takes place the thickness of the tape 10 will cause the spring member 12 to be urged downwardly, increasing the tension opposite the feed element and releasing the engagement of the grippers 11 and 12. It will therefore be seen that simultaneously with 15 the beginning of the feeding period the grippers will release to permit the tape to be freely moved, and simultaneously with the termination of the feeding period, the grippers are restored to normal gripping position, thereby holding the tape against either 20 forward or retrograde movement. The period of feeding may be varied substantially to increase or decrease the length of tape fed, by making a relative adjustment of the 25 two segmental rollers as heretofore described. The actuating pin 19, however, is carried by the particular segment which determines the end of a period of feeding and this pin will therefore operate upon the 30 cam surfaces 25 and 26 to produce a shearing action at or after the end of the feeding period.

The different functions of the spring strip 12 should be particularly noted. The fact 35 that this strip serves as a bed or support for the tape or web in its passage through the machine; the fact that it co-operates with the rotatable feed element to press the tape against the same and the fact that by 40 reason of this last co-operation, it provides an automatic grip and release mechanism for holding the tape between the feed periods, are all of importance.

As many changes might be made in the 45 above construction and as many apparently widely different embodiments of the invention could be made without departing from the scope thereof, it is intended that all matter set forth in the above description or 50 shown in the accompanying drawings shall be interpreted as illustrative and not in a limiting sense.

What I claim is:—

1. In a device of the character described 55 in combination, a support, a pair of web-grippers, one of said grippers being yieldable to permit feeding of the web, and a web-feeder having a segmental feeding surface arranged to feed the web and to hold 60 said yieldable gripper in an open position so long as said segmental feeding surface is in engagement with said web.

2. In a device of the character described 65 in combination, a support, a pair of web-grippers, one of said grippers being yield-

able to permit feeding of the web, and a web-feeder having a segmental feeding surface adjustable in length arranged to feed the web and to hold said yieldable gripper in an open position so long as said segmental feeding surface is in engagement with 70 said web.

3. In a device of the character described in combination, a support, a pair of web-grippers, one of said grippers being yieldable to permit feeding of the web, and an intermittently effective web-feeder having a segmental feeding surface arranged to feed the web and to hold said yieldable gripper in an open position so long as said segmental feeding surface is in engagement with 75 said web.

4. In a device of the character described in combination, a support, a rotatable web-feed member thereon, a fixed web-gripper thereon, and a yielding member adapted to co-act with said web-feed member to feed a length of web and adapted to co-act with said web-gripper member to grip and release the web accordingly as the web-feed 80 is inoperative or operative.

5. In a device of the character described in combination, a support, a rotatable web-feed member thereon comprising means for varying the length of effective feeding, a 95 fixed web-gripper member thereon, a yielding member adapted to co-act with said web-feed member to feed a length of web and adapted to co-act with said web-gripper member to grip and release the web accordingly as the web-feed is inoperative or operative, a cutter, and means comprising a member carried by the first said means adapted to actuate said cutter to sever the web when a length has been fed.

6. In a device of the character described in combination, a support, a pair of web-grippers, one of said grippers being fixed and the other being yieldable to permit feeding of the web, and a rotatable web-feed member comprising a plurality of co-axial segments adjustable relatively into different angular positions to provide different lengths of feeding surface; said web-feed member being adapted to hold said yieldable gripper in an open position so long as said feeding surface is in engagement with said web.

7. In a device of the character described, a support, a rotatable web-feed member thereon comprising a plurality of co-axial segments adjustable relatively into different angular positions to provide different lengths of feeding surface, a fixed web-gripper member, a resilient member adapted to co-act with said web-feed member to feed a length of web and adapted to co-act with said web-gripper member to grip and release the web accordingly as the web-feed is inoperative or operative, a cutter, and means comprising a member carried by said 120

125

130

web-feed member adapted to actuate said cutter to sever the web when a length has been fed.

8. In a device of the character described
5 in combination, a support, a rotatable web-
feed member thereon, a fixed web-gripper
member thereon, a yielding member adapted
to co-act with said web-feed member to feed
a length of web and adapted to co-act with
10 said web-gripper member to grip and release
the web accordingly as the web-feed is inop-
erative or operative, a cutter and means con-
trolled by the action of said rotatable web-
feed member adapted to actuate said cutter
15 to sever the web when a length has been fed.

9. In a device of the character described
in combination, a support, a rotatable web-
feed member thereon comprising a plurality
20 of segments adjustable relatively into differ-
ent angular positions to provide differ-
ent lengths of feeding surface, a fixed web-
gripper member, a yielding member adapted
to co-act with said web-feed member to feed
a length of web and adapted to co-act with
25 said web-gripper member to grip and release
the web accordingly as the web-feed is inop-
erative or operative, a cutter and means con-
trolled by the action of said rotatable web-
feed member adapted to actuate said cutter
30 to sever the web when a length has been fed.

10. In a device of the character described
in combination, a support, a pair of web-
grippers, one of said grippers being yield-
able to permit feeding of the web and a ro-
35 tatable web-feed element journaled in said
support comprising a plurality of axially
aligned relatively adjustable feeding seg-
ments whereby the length of the feed may
be varied; said web-feed element being ar-
40 ranged to feed the web and to hold said yield-
able gripper in an open position so long as
said web-feed element is in engagement with
said web.

11. In a device of the character described
45 in combination, a rotatable web-feed ele-
ment having a non-continuous peripheral
feeding surface, and a web-gripper member;
said member being normally in such close
proximity to said web-feed element that the
50 web holds said member in an open position
to permit feeding so long as the said feeding
surface of said feed-element is in engage-
ment with said web.

12. In a device of the character described
55 in combination, a rotatable web-feed element
having a non-continuous peripheral feeding
surface and a web-gripper member having a
yieldable portion adapted to be thrown into
an open position to permit feeding of the
60 web by the feeding surface of said web-feed
element, and to be held in said open position
so long as the feeding surface of said web-
feed element is in engagement with the web.

13. In a device of the character described,
65 in combination, a fixed gripper, a yieldable

gripper normally adapted to coöperate with
said fixed gripper to hold a web against
feeding and means for feeding the web; said
feeding means having a non-continuous
feeding surface which is adapted to engage
70 and feed said web and to hold said yield-
able gripper in an open position to permit
feeding so long as the said feeding surface
is in engagement with said web.

14. In a device of the character described,
75 in combination, a fixed gripper, a yieldable
gripper normally adapted to coöperate with
said fixed gripper to hold a web against
feeding and rotatable means for feeding the
web; said feeding means having a non-con-
80 tinuous feeding surface which is adapted
to engage and feed said web and to hold
said yieldable gripper in an open position
to permit feeding so long as the said feeding
surface is in engagement with said web. 85

15. In a device of the character described,
in combination, a fixed gripper, a yieldable
gripper normally adapted to coöperate with
said fixed gripper to hold the web against
feeding and serving as a bed for said web,
90 and rotatable means for feeding the web;
said feeding means having a non-continuous
feeding surface which is adapted to engage
and feed said web and to hold said yieldable
gripper in an open position to permit feed-
95 ing so long as the said feeding surface is in
engagement with said web.

16. In a device of the character described,
in combination, a fixed gripper, a yieldable
bed, normally adapted to coöperate with said
fixed gripper to hold a web against feeding
and to serve as a bed for the web, and means
100 for feeding the web; said feeding means
having a non-continuous feeding surface
adapted to hold said bed in an open position
so long as the feeding continues.

17. In a device of the character described,
in combination, a fixed gripper, a yieldable
gripper normally adapted to coöperate with
said fixed gripper to hold a web against feed-
110 ing and to serve as a bed for the web, and a
segmental feed element for feeding the web,
said element being arranged in such close
proximity to said bed that said bed is held in
an open position so long as the web is fed. 115

18. In a device of the character described,
in combination, a fixed gripper member, a
yielding bed adapted normally to coöperate
with said fixed gripper to hold a web and a
non-continuous feed member adapted to be
120 rotated in proximity to said bed to feed the
web and to hold said bed in an open position
so long as the feeding continues.

19. In a device of the character described,
in combination, a support, a web bed com-
prising a spring strip fixed to said support,
a non-continuous feed member adapted to be
rotated in proximity to said bed to coöper-
ate therewith to grip and feed a web, and a
fixed gripper member adapted to co-act with 125
130

a free end of said spring strip to release the web during the period of feed and grip the same after the feeding period.

20. In a device of the character described, 5 the combination, a support, a segmental feed element journaled therein, a coöperating feed element comprising a resilient member secured to said support on one side of said segmental element, and a gripper member 10 secured at the opposite side of said segmental element, said resilient member extending to coöperate with said gripper member whereby the segmental element in feeding operation may urge the resilient member to 15 a position of web release and the latter may automatically return to cause gripping of the web at the end of the feed.

21. In a device of the character described, in combination, a rotatable feed element 20 having a segmental feeding surface for intermittently feeding a web, a fixed gripper, a yieldable bed disposed below said feed element and adapted normally to coöperate with said fixed gripper to hold said 25 web between the feeding movements, said bed being so arranged with respect to the feeding surface of said feed element that said surface, while feeding, holds said yield-

able bed in an open position permitting it to return to a closed position after said feeding surface has disengaged from said web.

22. In a device of the character described, in combination, a rotatable feed element for intermittently feeding a web, comprising a plurality of relatively angular adjustable 35 fragmental disks having a common axis, a resilient bed disposed below said element and adapted to coöperate therewith to produce the feeding action, cutting means, and means for actuating said cutting means comprising an operating member on one of said disks.

23. In a device of the character described, the combination of a rotatable web-feed element having a non-continuous peripheral 45 feeding surface, and a yieldable web-gripper member over which a web is fed; said member being normally in such close proximity to said web-feed element that the web holds said member in an open position to 50 permit feeding by said web-feed element so long as the said feeding surface of said element is in engagement with said web.

In witness whereof, I hereunto set my hand this twenty-first day of April, 1920. 55
ALFRED B. WALES.
